UNITED STATES PATENT OFFICE.

THOMAS A. WESTON, OF STAMFORD, CONNECTICUT, ASSIGNOR TO THE YALE
& TOWNE MANUFACTURING COMPANY, OF SAME PLACE.

HOISTING MECHANISM.

SPECIFICATION forming part of Letters Patent No. 400,150, dated March 26, 1889.

Application filed April 14, 1888. Serial No. 270,706. (No model.)

To all whom it may concern:

Be it known that I, THOMAS A. WESTON, of Stamford, in the county of Fairfield and State of Connecticut, have invented certain new and 5 useful Improvements in Hoisting Mechanism, of which the following is a specification.

My invention in "sun-and-planet geared" portable and fixed hoisting mechanism is the subject-matter of a division of a pending application filed by me in the United States Patent Office October 10, 1887, Serial No. 251,953, employing a corresponding general arrangement of the main parts—that is to say, the main lifting-sheave placed within the machine between the two frame sides and upon the hollow shaft, the driving-pulley exterior to the frame on one side of the machine, and a system of sun-and-planet gearing exterior to the frame on the other side of the machine—10 by which I obtain a compact and symmetrical construction of a sun-and-planet-gearred hoist with the minimum of friction and with the load-chain and suspension-hook very nearly in the vertical central line of the machine; 15 but in place of the self-checking and brake devices shown in said application I combine with the driving-sheave the safety lowering device of my United States Patent No. 320,317, granted June 16, 1885, and to the internal annular gear-wheel of the sun-and-planet gearing I apply an external brake, making the 20 said wheel separate from the frame and capable of free rotation thereon. Further, where it is desired that the main lifting-sheave be 25 driven by a ratchet-connection with its shaft, I employ a peculiarly strong pawl and pivot of novel form.

My invention consists in the organizations of parts, which I will now describe in detail, 30 and then succinctly specify in my claims.

Figure 1 is an elevation of the geared side of my improved hoist. Fig. 2 is a vertical transverse section. Figs. 3, 4, and 5 represent my improved ratchet-connection applied to 35 the shaft B and main sheave A.

A is the main or lifting sheave, keyed to its hollow shaft B. A suitably-fitted lifting-chain, with an attached hook, as usual, (not illustrated,) is placed upon the sheave A. The 40 hollow shaft B is carried by suitable bearings in the frame sides D and E.

C is the driving-pulley, made to receive an ordinary endless hand-chain, and it is provided with a self checking and lowering device, substantially as shown in the specification of my United States Patent No. 320,317, June 16, 1885, and referred to particularly in claims 1, 2, and 3 thereof. The pulley C has its boss internally screw-threaded to fit a corresponding screw-thread upon the 55 shaft C', so as in the act of hoisting to compress by screw action against the resistance of the load and the collar C³ the friction-disks P' within the disk-box and ratchet-wheel P, and thus couple together the driving-pulley 60 C and shaft C', disks P', and ratchet-wheel P. The pawl P³, hung to the frame side E, prevents backward motion in the ratchet-wheel P. The shaft C' has made integral therewith the pinion C², engaging with the planet-pivots B⁴, which latter turn upon studs or pivots B³, carried by the flange B' of the hollow 65 shaft B.

B² is a ring or frame attached to the flange B', the better to support the pivots B³. The 70 pinions B⁴ also engage with the internal annular gear-wheel, D', which is capable of rotation upon the bearing D⁴ upon the frame side D. The periphery of the wheel D' is 75 embraced by a brake-strap, D⁵.

D⁶ is the brake-lever, fulcrumed upon the projecting end of the cross-head and frame-stay F.

D⁷ is a strong spring of any convenient form secured to the frame D, whereby the lever D⁶ 80 is pressed continually, so as to strain the attached strap D⁵ around the brake-rim of the internal annular gear-wheel, D', sufficiently to prevent its backward rotation even under a maximum load.

To the long arm D⁸ of the lever D⁶ a cord, D⁹, is attached, for convenience in pulling off the brake-strap D⁵. Upon releasing the brake-strap D⁵ sufficiently by its lever D⁶, so that any load upon the hoist begins to descend, 85 the accompanying backward rotation of the sheave A, shaft B, and flange B' will carry the pinions B⁴ around the now stationary pinion C², the said pinion C² and its shaft and the driving-pulley C being frictionally locked 90 together and pawled to the frame by the pawl P³, as already explained. The said backward 95 100

rotation of the pinions B^4 around the now fixed pinion C^2 impels the internal annular gear-wheel, D' , with them in the same direction against the brake-strap with a multiplied velocity. The larger number of revolutions thus made by the internal annular gear-wheel, D' , over those of the hollow shaft and main sheave adds largely to the efficiency and controlling-power of the brake-strap, rendering very easy the control of the load by the lever D^6 and cord D^9 . Upon the latter being released by the operator the spring D^7 resumes its action upon the strap and arrests the descent of any load suspended upon the hoist. Slow or safety lowering is effected by overhauling backward the hand-chain upon the driving-sheave C .

In this construction of a sun-and-planet geared hoist I have thus combined in one machine a slow and safe lowering action with a more rapid one, but one easily controlled, each device being always available for use at the instant it is required.

I have illustrated my invention as embodied in a portable hoist or geared pulley-block; but it is also obviously adapted for a stationary frame attached to a crane or other support.

The periphery of the main lifting-sheave I have shown as formed to engage with the links of a pitch-chain; but it may, where desired, have a smooth cylindrical exterior suited for coiling thereon a rope, or it may be toothed to engage with the teeth of a rack-lifting bar as a substituted device for reaching the load to be overcome, all these being usual and well-known devices and therefore not illustrated.

Figs. 3, 4, and 5 represent a ratchet device applicable to the shaft B and sheave A^8 , so as to provide the facility for running rapidly upward the chain and hook when unloaded by pulling upon the slack or unloaded end thereof.

Fig. 3 is an elevation showing the sheave A in section.

Fig. 4 is a side elevation of the sheave A and internal ratchet-teeth, the pawl in dotted lines.

Fig. 5 is a side view of the pawl-disk and parts carried thereon.

The sheave A^8 is loose upon the shaft B , and kept in place between the solid collar B^5 and the pawl-disk A^2 , the latter being keyed to the shaft B .

A' is a circle of internal ratchet-teeth formed within the side flange of the sheave A^8 . Upon the side of the disk A^2 a projec-

tion, A^3 , is cast to support the pawl-pivot A^4 at its exposed end against yielding to the pressure of the pawl A^5 . The pawl A^5 has an open bearing at its end, by which it is seated upon the upper exposed side of the pin or pivot A^4 , and it is kept to its seat by the small screw A^6 , passed through an ear or thin continuation of the pawl side extended over the outer circular end of the pivot A^4 , as shown in Figs. 3 and 5. A spring, A^7 , of any convenient form is used to hold the pawl to the teeth in the usual way. This construction of pawl, pawl-pivot, and support furnishes compactness and maximum strength in the pivots, where such devices are usually weakest.

I claim as my own invention—

1. The combination, with a hoist-frame, of a driving-pulley provided with a safety lowering device exterior to the hoist-frame upon one side thereof, a train of sun-and-planet gearing provided with a friction-brake exterior to the hoist-frame upon the other side thereof, and a main lifting-sheave within the hoist-frame, substantially as set forth.

2. The combination, with a hoist-frame, of a driving-pulley, C , connected by a safety frictional lowering device with the driving-shaft C' , a ratchet-wheel, P , and pawl or check device, P^3 , and a train of gearing provided with a friction-brake, substantially as set forth.

3. The combination, with a hoist-frame, of a gearing consisting of the driving-sheave C , driving-shaft C' , having pinion C^2 , pinions B^4 , pivoted to the driving-flange B' , annular wheel D' , and a brake whereby the said internal annular gear-wheel is frictionally coupled with the hoist-frame or released therefrom, hollow main shaft B , attached to the flange B' and journaled at each end in a bearing in the hoist-frame, and a lifting-sheave, A , attached to the shaft B , substantially as set forth.

4. The combination, with the shaft B , of the sheave A^8 , provided with the internal ratchet-teeth, A' , and loose upon the shaft, a collar, B^5 , and the pawl-disk A^2 , provided with the projection A^3 and keyed to the shaft B , and the pivoted spring-pawl A^5 , substantially as set forth.

In testimony whereof I have hereunto subscribed my name.

THOS. A. WESTON.
